UNITED STATES PATENT OFFICE.

LEON A. DOUGLAS, OF WINDSOR, ONTARIO, CANADA.

SURGICAL INSTRUMENT.

Application filed February 28, 1921. Serial No. 448,532.

To all whom it may concern:

Be it known that I, LEON A. DOUGLAS, a subject of the King of Great Britain and Ireland, residing at Windsor, in the Province of Ontario and Dominion of Canada, have invented certain new and useful Improvements in Surgical Instruments, of which the following is a specification, reference being had therein to the accompanying drawings.

The invention relates to surgical instruments of that type used for the removal of the tonsils, and the invention consists in various features of construction as herein-
15 after set forth.

In the drawings:

Figure 1 is a plan view of the instrument;

Figure 2 is a side elevation thereof;

Figure 3 is an enlarged longitudinal section showing the instrument as in use;

Figure 4 is a plan view of Figure 3;

Figure 5 is a cross-section on line 5—5 of Figure 2.

In the present state of the art tonsil-removing instruments have been devised comprising a clamp for squeezing the flesh adjacent to the portion which is to be severed, thereby preventing hemorrhage, and a knife 25 slidable adjacent to said clamp for effecting the severing. It is, however, usual to have the knife arranged to sever by a movement in a direction away from the operator and there is therefore always danger of cutting too far. One of the features of my improvement is in the arrangement of knife which is moved in a direction toward the operator during the severing operation, thereby avoiding all possible danger of cutting any part other than the part which it 35 is desired to remove.

For holding the instrument during the clamping and severing action, it is desirable to provide a handle to be grasped by the surgeon, but where the tonsils on each side of the mouth are to be removed, the handle of the instrument on one side will interfere with that of the instrument on the other side. It is therefore another feature 45 of my invention to provide a removable handle and one which may be quickly disengaged from or attached to the instrument.

In detail, A is a bar or strip for insertion 50 into the mouth and having at its inner end an aperture B therethrough bounded on its

inner side of the segmental clamping jaw C. D is a cooperating clamping jaw having a parallel segmental face, said jaw being slidably engaged with guide-ways E upon 60 opposite sides of the member A. Intermediate the members D and A is a flat shank F, which at its inner end is apertured in registration with the aperture B, as indicated at G. The portion of the member F on the 65 inner side of said aperture forms a knife having its cutting edge facing outward, said portion being of segmental form for registering with the segmental jaw member C, as indicated at H. The members A, D and F 70 extend outward parallel to each other and the member F is provided with laterally extending finger pieces I, which may be grasped to draw said member outward and to cause the severing by the blade H. The 75 member D has at its outer end a laterally projecting lug J, on which is mounted a rotary cam K for engagement with a cooperating bearing L on the member A, the arrangement being such that by rotating said 80 cam a powerful squeezing movement of the jaws C and D towards each other is effected. M is a winged handle for rotating the cam K.

For holding the instrument there is provided a handle N which is detachably engaged with the outer end of the member A. This handle is preferably formed by a wedge-shaped lug O depending from the member A and having a dove-tail engagement with a corresponding recess in the handle N. Thus the handle may be engaged by merely moving it laterally upon the wedge over the small end thereof, and it is then locked by a catch P which is 90 pivoted at Q and has a spring R for forcing the hooked end P' thereof into engagement with the lug O. This catch is located in a groove in the handle and may be released by pulling downward the hook so as 95 to permit the handle to be detached.

In operation, the instrument is first adjusted into position, where the jaw D is retracted and the severing blade H is forward in registration with the jaw segment C. In this position the tonsil may be passed through the aperture B, after which the jaw D is moved in a direction away from the operator and clamped by the operation of the cam K. The finger pieces I may then be grasped and by pulling thereon in a direction toward the operator the blade 110

H will be moved forward, severing the protruding portion of the tonsil. If the operation is to be performed on both sides of the mouth, the handle N may be detached and another instrument used in the manner just described. Finally the clamp is released by the reverse rotation of the handle M and this permits removal from the mouth.

10 What I claim as my invention is:

1. A surgical instrument comprising a member for insertion in the mouth, cooperating clamping and severing members associated therewith, a handle for supporting said members, and a detachable engagement between said handle and first-mentioned member comprising a wedge-shaped member on one engageable with the other which has a correspondingly shaped recess in the other, and a pivoted catch for holding said members in engagement.
2. A surgical instrument comprising a member for insertion in the mouth, cooperating clamping and severing members associated therewith, a wedge-shaped lug depending from the first mentioned member, a removable handle having sliding engagement with the said lug, and spring influence means for retaining said handle in position upon the lug.
3. A surgical instrument having a member with a wedge-shaped lug depending therefrom, a removable handle having slid-

ing engagement with said lug, and pivoted spring influence means for retaining said handle in position upon the lug.

4. A surgical instrument comprising an operating portion, a handle for supporting said portion, and a detachable engagement between said handle and said operating portion comprising a wedge-shaped member on one and the other having a correspondingly shaped recess, and a pivoted catch for holding said members in engagement.

5. A surgical instrument comprising an operating portion, a handle for supporting said portion, and a detachable engagement between said handle and said operating portion comprising a wedge-shaped member on one and the other having a correspondingly shaped recess, and a pivoted catch for holding said members in engagement.

6. A surgical instrument comprising an operating portion, a handle for supporting said portion, and a detachable engagement between said handle and said operating portion, comprising a wedge-shaped member on one and the other having a correspondingly shaped recess and a groove in one of its sides, and a catch pivotally mounted in said groove for holding said members in engagement.

In testimony whereof I affix my signature.

LEON A. DOUGLAS.
